UNITED STATES PATENT OFFICE.

FRANK D. PEARNE, OF CHICAGO, ILLINOIS, ASSIGNOR OF ONE-HALF TO JAMES E. MARTINE, OF CHICAGO, ILLINOIS.

PRINTING-TELEGRAPH APPARATUS.

1,146,274.

Specification of Letters Patent. Patented July 13, 1915.

Application filed September 3, 1907. Serial No. 391,020.

To all whom it may concern:

Be it known that I, FRANK D. PEARNE, a citizen of the United States, residing at Chicago, county of Cook, State of Illinois, have 5 made a certain new and useful Invention in Printing-Telegraph Apparatus, of which the following is a specification.

This invention relates to printing telegraph apparatus, and particularly to the apparatus employed at the sending end of the line.

The object of the invention is to provide an apparatus of the nature referred to which is simple in construction and arrangement, 15 and efficient and reliable in operation.

A further object is to provide a printing telegraph sending apparatus of such construction and arrangement that a series of electrical impulses may be sent in rapid succession over a line wire and which impulses may all be of a given strength, or of different strengths, or may be positive or negative, as may be required.

A further object is to provide an apparatus of the class referred to wherein various combinations of electrical impulses may be sent over the line wire to effect the printing operation at the distant or receiving end of the line, the sending of such combinations of impulses being controlled automatically by the depressing of keys, or otherwise, at the sending station.

A further object is to provide an apparatus of the class described wherein efficient 35 control is maintained over the various parts.

Other objects of the invention will appear more fully hereinafter.

The invention consists substantially in the construction, combination, location and arrangement of parts, all as will be more fully hereinafter set forth, as shown in the accompanying drawings, and finally pointed out in the appended claims.

Referring to the accompanying drawings, 45 and to the various views and reference signs appearing thereon,—Figure 1 is a diagrammatic view illustrating the operation of the keys of the key board and the circuits controlled thereby, and also illustrating the action of the carriage return and the shift keys. Fig. 2 is a diagrammatic view illustrating the wiring connections of the relay spools of the mechanism employed in selecting and distributing the impulses to be

sent over the line wire with the depression 55 of the keys of the key board. Fig. 3 is a diagrammatic view illustrating the wiring connections of the selecting and distributing apparatus. Fig. 4 is a view somewhat diagrammatic, showing the wiring connections 60 of the sending apparatus. Fig. 5 is a top plan view of the apparatus employed for sending the selected and distributed impulses to the line wire. Fig. 6 is a view in side elevation of the same. Fig. 7 is a broken 65 view in section of a magnetic clutch employed in connection with the sending apparatus. Fig. 8 is a face view of one member of the magnetic clutch shown in Fig. 7. Fig. 9 is a similar view of the other member 70 of the magnetic clutch. Fig. 10 is a broken view in side elevation of the clutch member shown in Fig. 9. Figs. 11, 12, 13, 14, a 15, are detail views of various contacts employed in connection with the sending 75 apparatus shown in Figs. 4, 5 and 6. Figs. 16, 17 and 18 are, respectively edge, face and top plan detail views of the escapement employed in connection with the sender. Figs. 19 and 20 are detail views of 80 the stop arms employed in connection with the escapement.

The same part is designated by the same reference sign wherever it occurs throughout the several views.

85

In a printing telegraph apparatus embodying the principles of my invention I propose to send a series of electrical impulses in quick succession over a line wire to operate the receiving apparatus at the distant 90 station. Inasmuch as the present invention concerns itself only with the apparatus for selecting controlling distributing and sending such impulses it is unnecessary to show or describe the receiving apparatus. The 95 electrical impulses to be sent over the line wire may be of any desired or suitable character. In the particular form shown, but to which my invention is not to be limited or restricted, I employ impulses of four different characters, namely, a strong positive current, a weak positive current, a strong negative and a weak negative. It is obvious that other forms or variations may be employed, but these variations, above named, 100 are sufficient for purposes of illustration. I also propose to send said impulses in groups of three each, though in this respect I do 105

not desire to be limited or restricted. When impulses are thus sent out in groups of three, employing four different kinds of current, it is obvious that, by a simple arithmetical permutation, sixty four different groups or combinations may be sent out, by simply varying the relative order or succession of the different characters of current employed. Each group or combination is sufficient to cause a letter to be reproduced or printed at the distant end of the line.

It is obvious that if additional variations of current strength be employed the number of possible permutations or combinations may be very largely increased. The apparatus which I employ to select, distribute and send to line these various groups or combinations of impulses, and which forms the subject matter of the present application may, for purposes of description, be divided into three parts, namely, the key board, the distributor and the sender.

The key board may be of any suitable or convenient construction and arrangement, similar, for instance, to the key board of a double shift key typewriter, such, for example, as the ordinary Blickensderfer No. 5, or the Blickensderfer electric typewriter, and the keys consist of the ordinary pivoted or movable typewriter keys, so arranged that when any one is depressed or moved, it will close a circuit through a coöperating group of three relays employed in connection with the distributor part of the apparatus.

The distributor, which is controlled by the keyboard, includes relays the circuits of which are controlled by the keys of the keyboard. In the particular form shown as illustrating the principles of my invention, but to which my invention is not to be limited or restricted, the distributor includes twelve relays, and when a key of the keyboard is depressed it closes circuits through a corresponding group of three of such relays, thereby selecting the particular group or combination of impulses corresponding to the particular key which has been depressed, and connecting the circuits of said selected groups or combinations of impulses to the proper and corresponding contacts of the sender apparatus through which the proper line connections therefor are made. Each of the distributor relays controls three sets of contacts, one of which closes a local or locking circuit through its own relay coil, another completes a series of contacts, one for each relay in the particular group operated, for completing circuit to the sender to start it into operation, and the third set connects the line circuit to the contact springs which, through the operation of the sender, makes and breaks such line connection in rapid succession. The shift keys of the keyboard each have separate circuits, whereby one circuit is made when such key

is depressed, and another circuit is made when such key is released, the purpose and function of which will be explained herein-after.

The sender comprises means for completing the proper connections in rapid succession, and is automatic in its operation and effects the line connections of the various characters or strengths of current employed in each group or combination, according to and as determined and selected by the key and distributor.

This is a brief outline of the general purposes and functions of the apparatus which I have selected for the purpose of illustrating the principles of my invention and as shown, and as embodied in the construction and arrangement shown in the accompanying drawings, and the best form in which I at present contemplate carrying my invention into practical operation, though it is understood that my invention is not to be limited or restricted to the particular form, construction and arrangement shown and hereinafter to be described, as the principles thereof may well be embodied in a wide variety of apparatus.

I will first describe the mechanical construction and operation of the sender. Upon a suitable base 200, are mounted standards 201, see Figs. 5 and 6, in which is journaled a shaft 83, to which continuous rotations are imparted through a gear wheel 100, mounted thereon, from any suitable or convenient source of power. In practice I prefer to drive shaft 83 at a high speed say one thousand revolutions per minute. Mounted upon shaft 83, to rotate therewith are contact rings 81, 82 and the member 79, of a magnetic clutch. With the contact rings 81, 82, coöperate respectively contact springs 101, 102. Mounted upon shaft 83 is a sleeve 84. Carried by said sleeve to revolve therewith is a clutch member 80 and a hub 202, provided with stop arms 77, 78, extending radially in diametrically opposite directions. The clutch member 80 coöperates with the magnetic clutch member 79, to couple the sleeve 84, and shaft 83 to rotate together when the coil of clutch member 79 is energized. Also mounted upon sleeve 84, to revolve therewith is a drum 61, carrying heavy insulating blocks 203. Also mounted upon to revolve with, but insulated from, sleeve 84, are contact rings 85, 86 and 112. The latter is in the form of a divided commutator having the half cylinder sections 65 and 66, insulated from each other. Bearing upon and coöperating with the commutator 112, is a contact spring 111. Similarly, the contact springs 109, 110 bear upon and coöperate respectively with the contact rings 85 and 86. Pairs of contacts 103, 104, 105, 106, 107 and 108, are arranged adjacent the drum 61, and the members of each pair are 109

insulated from each other and are adapted to be closed upon each other by the insulating blocks 203, on the drum 61. These blocks are so relatively arranged as to cause 5 the members of the pairs of contacts to be closed upon each other in succession during each half revolution of the drum. In practice I arrange one pair of contacts, as 108, see Figs. 5, 6 and 15, to remain closed upon 10 each other whenever the drum 61 completes each half revolution and comes to rest. It is obvious that as many pairs of contacts 103, 104, 105, 106, 107, 108, as may be desired may be employed. Coöperating with 15 the stop arms 77, 78, is an escapement 76, having the fork arms 86, 113. This escapement is controlled by an electro-magnet 73, a pole piece 205, carried by escapement 76 being attracted by said magnet, when the 20 latter is energized, and against the action of a spring 206. In normal position of the parts when the sleeve 84 is at rest, one or the other of the stop arms 77, 78, bears against the fork arm 113, of the escapement, 25 as shown in Fig. 6 thereby locking the sleeve against rotative movement. As above explained the sleeve 84 is designed to remain at rest until the member 79 of the magnetic clutch is energized, thereby effecting a 30 rotative movement of the coöperating clutch member 80, which constitutes the armature of the clutch, the members 79, 80, being respectively carried by the shaft 83, and the sleeve 84. Consequently whenever the 35 circuit of the magnetic clutch member 79 is completed, the sleeve 84 is coupled to rotate with shaft 83. Before the completion of the circuit of the magnetic clutch, however, it is desirable to operate the escapement 76, in 40 order to release whichever one of the stop arms 77, 78, that may be bearing against the fork arm 113, of said escapement. Whenever, therefore, it is desired to start up the 45 sender, the circuit of magnet 73 is completed, thereby rocking the escapement 76. When this escapement has completed about one half of its movement under the influence of the attractive force of the magnet 73, the stop arm 77, in the instance shown is 50 released and hence the sleeve 84, is free to rotate. At the same time the tail of the escapement engages a pair of contacts 63, and separates them. The separation of the members of the pair of contacts 63, causes current 55 to flow through the clutch magnet, thereby initiating the rotative movement of the sleeve 84. However only a half revolution is thus imparted to the sleeve 84, and the various parts carried thereby, since 60 the circuit of the clutch magnet includes the divided commutator 112, and at each half revolution of said commutator the contact spring 111, passes from one of the segments 65, 66, to the other thereby opening the circuit. At the same time the circuit 65 of the clutch magnet is broken the prong or fork 86, of the escapement 76, has been brought into the path of the other stop arm 78. Since the circuit of magnet 73 was not broken at the same time with that of the 70 clutch magnet, the escapement 76, is held in position for the prong 86, thereof to obstruct the stop arm 78. This relation of the parts is maintained until the circuit of magnet 73 is broken, and, as will be more fully 75 explained hereinafter, the circuit of the escapement controlling magnet is not broken until current coming from the distributor is cut off, or, in other words, until the key which has been depressed is released. 80

The actuation of the escapement 76, in advance of the actuation of the magnetic clutch I regard as a desirable and important feature for the reason that thereby the stop arm 77 or 78, as the case may be, is released before power is applied to the sleeve 84, to rotate the same. Otherwise, the application of rotative power to the sleeve would cause the stop arm which is bearing against the escapement to press the harder against said 85 escapement and hence render the operation thereof difficult. By completing the circuit of magnet 73, however, in advance of the completion of the circuit of the coil of the magnetic clutch the stop arm is released before the rotative power is applied to the sleeve, and hence the parts are enabled to 90 work easily and smoothly.

By reference to Fig. 5 it will be seen that the end of the stop arm is triangular in 100 shape, and by reference to Fig. 18, it will be noticed that the prong or fork 113, of the escapement, is not as broad as prong or fork 86, consequently, when the circuit of magnet 73, is broken, that is, when the depressed key of the keyboard is released, the escapement 76, is restored to its normal position by the retractile spring 206, thereby bringing the prong or fork 113, into position for the stop arm 78, or 77, to bear thereagainst, 110 the flat side of the triangular shaped stop arm bearing against the prong or fork, while the edge thereof presented toward the other prong or fork 86, clears said prong, as clearly shown in Fig. 4, and insures the 115 ready passage of the stop arm between said prongs or forks when the escapement is again actuated by the completion of the circuit of magnet 73, that is, when the next key of the keyboard is depressed. 120

As above noted, the members of the six pairs of contacts are shown as being successively closed upon each other with each half revolution of the drum 61, and one pair, 108, are left closed upon each other 125 when the drum completes its half revolution. The object of thus leaving the contacts 108, closed upon each other during the time the drum remains stationary, that is, while the automatic sender is not in use for 130

sending impulses to the line, is to keep the line grounded at all times while the sender is not in use thereby enabling impulses to be received from a distant station without 5 the necessity of the operator closing a switch to enable such impulses to be received.

As above noted, the number of pairs of contacts to be successively closed by each 10 half rotation of the drum 61, may be varied as desired and as required. In the particular form shown, to which, however, the invention is not to be limited, only the contacts 103, 105 and 107 are concerned in connecting the impulse circuits from the distributor to the line. The other contacts 104, 106, and 108 are employed to connect the line to ground after each impulse thereby enabling the line to be completely discharged after each impulse is sent thereover. This I regard as a valuable feature of my invention as it insures the best results.

From the foregoing description it will 25 be seen that I provide a sending apparatus for completing the impulse circuits to the line, and which sender, when once put into operation is automatic in action. It will also be seen that the sender is put into operation by the depressing of a key at the 30 keyboard. It will also be seen that the line and ground connections are effected by a rotating part, a complete cycle of operation being completed with each half revolution 35 of such part and consequently when the sender is once operated, it is not necessary to wait until said sender returns to a normal position before its operation may be repeated, but the apparatus is ready to repeat its operation over and over again by 40 the mere act of completing electric circuits. It will also be seen that the circuit of the clutch through which the rotative movements of the sender are effected is automatically broken at each half revolution of 45 the sender drum, and that the escapement devices allow only one stop arm to pass when a key is depressed and that no further operation of the sender is possible until 50 the key is released. It will also be seen that by employing the heavy insulating or hard rubber blocks 203 on the drum to close the members of the pairs of contacts, which co-operate therewith, upon themselves, the 55 heavy line currents are prevented from communicating with the drum or its gearing or supporting connections.

Other points of advantage connected with the construction of sender as above 60 shown and described will readily appear to persons skilled in the art and will be hereinafter set forth and claimed.

The arrangement of the distributor is 65 illustrated in Fig. 3. This part of the apparatus, in the form which I have selected to

illustrate the principles of my invention, includes twelve relays, each arranged to control several contacts. These relays, in the form shown, but to which my invention is not to be limited or restricted, are arranged 70 in three groups of four each. The relays of the first group are numbered respectively 1, 2, 3 and 4; those of the second group are numbered 5, 6, 7 and 8, respectively, and those of the third group are numbered 75 respectively 9, 10, 11 and 12. In Fig. 3 only one winding circuit of each of the relays is shown and this circuit is used simply to lock the relay in position after it has been operated.

In the operation of the apparatus embodying my invention the current to be sent to the line may be procured from any suitable or convenient source. I have shown two generators 13, 14, for this purpose. A 80 resistance 15, is arranged in connection with the positive side of generator 13, and a resistance 16, is arranged in connection with the negative side of the generator 14. One circuit from the positive side of the 85 generator 13, includes contacts, 207, 208 and 209, respectively, controlled by the relays 1, 5 and 9, said circuit containing no resistance, and consequently when either one of the relays 1, 5 or 9 is operated a strong positive 90 impulse or current is supplied to the contacts 103, 105 or 107, as the case may be, depending upon the particular relay which has been operated, and which contacts, 103, 105, 107, as above explained, are controlled 95 by the drum of the automatic sender and, at proper times are closed upon themselves to complete the circuits in which they are contained to the line. Another circuit from the 100 positive side of the generator 13 includes the 105 resistance 15, and also contacts 210, 211 and 212, respectively controlled by the relays 2, 6 and 10, and consequently when either of 110 said relays is operated a weak positive impulse or current is supplied to one or the other of the contacts 103, 105 or 107, depending upon the particular relay which has been operated. Similarly, one circuit from the negative side of the generator 14, includes 115 the resistance 16, and also contacts 213, 214 and 215, which are respectively controlled by the relays 3, 7 and 11, so that when either of said relays is operated a weak negative current or impulse is supplied to one or another of the contacts 103, 120 105 or 107, depending on the particular relay which has been operated. And another circuit from the negative side of the generator 14, containing no resistance, includes 125 contacts 216, 217 and 218, which are respectively controlled by relays 4, 8 and 12, so that when either of these relays is operated a strong negative current is supplied to a contact 103, 105 or 107, according to the particular relay operated. It will be ob-

served that each of the contacts 207, 210, 213 and 216 of the first group of four relays, 1, 2, 3 and 4 comprises a make-and-break, one part of each being normally closed when the relay is not in operation, and this part being broken and the other part closed when the relay is operated. It will also be seen that all the make parts of these contacts are in series with the line controlling contact 103, but that when any one of the relays is operated the part of the contact controlled thereby which is normally closed, is broken and the part which is normally open is closed thereby making it impossible to simultaneously operate more than one relay of the same group, and consequently only one relay of such group can be in operation at any one time. Thus, suppose the relay 2 to be operated to send a weak positive current to line, the normally closed part of make-and-break contact 210 which is in series with the similar parts of the make-and-break contacts 213 and 216, is broken thereby making it impossible to operate either of the relays 3 or 4. If, however, the relay 1, be operated while relay 2 is in operation, which, of course is possible, then the normally closed part of make-and-break contact 207 controlled by relay 1 would be opened, and as this part is in series with the contact 210 of relay 2, it follows that the operation of relay 1 would instantly render relay 2 inoperative, and consequently only one relay of each group can be effectively operated at a time. Similarly the contacts 208, 211, 214 and 217 of the second group of relays have the same construction, relation and operation with reference to their respective relays 5, 6, 7 and 8 and the line controlling contact 105. And the contacts 209, 212, 215 and 218 of the third group have the same construction relation and operation with reference to their respective relays 9, 10, 11 and 12, and the line controlling contacts 107. From this arrangement it will be readily seen that only one relay of each group is operated or energized at one time, but the operation of a relay in one group may be simultaneous with the operation of one relay only in each of the other two groups. In this manner I am enabled to send to the line the various groups or combinations of impulses which I have hereinabove explained, such combinations being made up of any three desired characters of current or impulses that is, a strong positive, a weak positive a weak negative and a strong negative. It is also obvious that the system may be readily extended to take care of or to accommodate additional variations of current strength by variously introducing additional resistances or otherwise, as may be desired.

From the foregoing description it will be seen that when relay 1, 5 or 9 is energized a

strong positive current circuit is completed to the line contact 103, 105 or 107 as the case may be; and when either of relays 2, 6 or 10 is energized a weak positive current circuit is completed to line contacts 103, 105 or 107, 70 as the case may be; and when either of relays 3, 7 or 11 is energized a weak negative current circuit is completed to contact 103, 105 or 107, respectively; and that when either of the relays 4, 8 or 12 is energized a 75 strong negative current circuit is, in like manner completed to contact 103, 105 or 107, as the case may be.

In the operation of the automatic sender and during each half revolution of the drum 80 61, the contact 103, is first connected to the line and then such connection is broken. Immediately thereafter the contact 104, is connected to the line, thereby grounding the latter, and then such connection is broken. 85 Next, the connection of contact 105 to line is made and broken, and then the line grounded through contact 106. Next and finally the connection of contact 107 to line is made and broken, and the line grounded through contact 108, the latter condition remaining until the sender is again operated. Thus the desired groups or combinations of impulses are selected and sent to line. Since only one relay of each group of the distributor can be 90 operated at one time, it is obvious that interference of positive and negative currents, or neutralization of the impulses is avoided. For instance, suppose relay 1 of the first group, relay 8 of the second group and relay 100 10 of the third group be energized at the same time. Thereupon a strong positive current circuit is completed to line contact 103, a strong negative to line contact 105, and a weak positive to the contact 107, and the half 105 revolution of the automatic sender completes these connections successively to the line. Thus it will be seen that by energizing the required combinations of relays any desired group or combination of impulses may be 110 sent to the line wire each of which is designed to produce a different result at the distant station.

I have above indicated that each relay of the distributor controls a series of contacts, 115 and I have described the operation and function of the make-and-break contact associated with each relay. Another contact controlled by each relay is a simple make, and it controls a circuit which serves to lock or hold the relay in its operated position. This contact is designated by reference sign 219, and all of the contacts 219 are so connected that when any one of the relays is energized a circuit is made through the contact 219, 120 associated therewith, and through a coil or winding of the relay which is sufficient to retain said relay energized until the locking circuit is broken. Included in this locking circuit are contacts 31, 30 which are con- 125 130

trolled by the automatic sender, or rather, by a relay 27, the circuit of which is closed only during the operation of the sender. This locking circuit may be traced as follows: from battery 18, Fig. 3, through wire 23, to wire 29, Fig. 4, contact 30, contact 31 (when relay 27 is energized) wire 32, Fig. 4, to wire 33, Fig. 3, and thence to one member of each contact 219. The other member of each contact 219, is connected through the locking coil of its associated relay, and thence to common return or ground 26. Thus it will be seen that two things are necessary in order to complete the locking circuit of any one of the distributor relays, namely, the relay 27, of the sender must be energized, that is, the sender must be in operation, and second, the distributor relay must be operated. When these two results occur, however, the particular distributor relay which has been energized is held or retained in its operated position until the sender has completed its work and the circuit of relay 27 is broken, thereby breaking the circuit between contacts 30, 31. By reason of this arrangement it will be readily seen that it is not necessary to hold down a key of the key board, when depressed, for any length of time, but only long enough to complete the energizing circuit of the relays affected by the act of depressing the key. This action is so rapid, however, that it is impossible to give even the lightest touch to the key without its inaugurating the cycle of operations necessary for sending to line the corresponding group or combination of impulses, as above explained, and when this cycle of operation is once inaugurated the various functions are accomplished automatically. This, I regard as a most important and valuable feature of my invention for the reason that thereby anyone, even one unskilled in the use of a typewriter is enabled to do good work in the use of my apparatus, as it is not necessary to press down the keys with any particular degree of pressure, nor to hold the keys depressed any particular length of time as is usually the case with apparatus of this nature, nor does any harm result by holding a key pressed down for too long a time since, as will be more fully explained hereinafter, no action can result by depressing a key until the previously depressed key is released and returns to its normal position.

Another set of contacts 220, is controlled by each of the relays of the distributor. These contacts are all included in a circuit which, when completed, effects the starting up of the automatic sender. For example take the same combination of distributor relays 1, 8 and 10, as before. When these relays are energized, and while they are performing their function of completing the line impulse circuits to the line contacts

103, 105 and 107, as above explained, they are also closing the sender starting circuit as follows: from battery 18, see Fig. 3, wire 23, through the contacts 220, of each of the relays 1, 8 and 10, wire 24, to wire 25, Fig. 4, to relay 27, wire 227, contacts 63, which at this time are closed upon each other, wire 64, segment 65, ring 67, wire 69, contacts 69, which at this time are also closed upon each other, where it divides, one part continuing through wire 70, the winding of relay 72, and to ground or return at 26, and the other part continuing through wire 71, one winding or coil of magnet 73, and to ground or return at 26. The completion of this circuit energizes relays 27 and 72, and the magnet 73. Relay 27, when energized, closes the locking circuit for the relays which have been energized, namely, in the instance taken for illustration, the relays 1, 8 and 10, by closing the contacts 30 and 31, upon each other. The energization of relay 72, by the closing of the circuit above traced, causes the members of contact 74, to separate thereby breaking the circuit which includes said contacts. The energization of said relay 72, also closes the members of contact 70, upon each other, thereby closing at that point, a circuit from wire 25, over which current is already flowing, as above mentioned, through wire 90, resistance 24, wire 225, contacts 73, wire 70, relay 72, to common return or ground at 26, thereby holding relay 72 in its operated position, as long as current continues to flow through line 25, that is, as long as the key is held down and the distributor relays remain energized. The energization of magnet 73, as above explained, causes the armature 205, carried by the escapement 76, to be attracted, thereby rocking said escapement and releasing the stop arm 77. Just as the escapement reaches the point where the stop arm 77, is released, it breaks the contact 68, and hence the circuit from wire 25, through relay 27, instead of passing through contacts 63, wire 64, and on, as above described, will pass through the relay 27, wire 227, wire 224, contact ring 81, the coil of magnet clutch 79, contact ring 82, wire 225, wire 64, and on as before described, thereby placing the magnetic clutch in commission and hence imparting rotative movement to the sleeve 84, and everything connected with it, the stop arm 77, passing through the escapement. However, by the time the stop arm 78, reaches the escapement in the rotative movement of the sleeve 84, that is, by the time said sleeve completes one-half a revolution, the brush or contact spring 111, has passed off of contact segment 65, of commutator 112, and onto the segment 66, thereby automatically breaking the circuit through the magnetic clutch 79, and the relay 27, thereby cutting off the rotating power applied to the sleeve 84.

84, and also causing the relay 27, to return to its normal inactive condition. By this time the stop arm 78, strikes against the prong 86 of the escapement and is thereby blocked against further rotative movement. During the half revolution imparted, as above described, to the sleeve 84, and the parts carried by it, the drum 61, has performed its duty of successively connecting the generator circuits as determined by the relays 1, 8 and 10, to line 22 through the line contacts 103, 105 and 107, with an intermediate line connection to ground, and at the completion of the movement leaves the line connected to ground through the ground contacts 108, as above explained. By the breaking of the circuit of relay 27, and the return of said relay to normal, the locking circuit of the distributor relays 1, 8 and 10, which, in the example given, have been operated, is also broken. But these relays do not return to the normal or inactive position upon the breaking of their locking circuit, if the key of the key board which was depressed in the first instance remained depressed, for, suppose the key is held down, then current will continue to flow from battery 18, Fig. 3, to wire 23, wire 24, to wire 25, Fig. 4, wire 90, and resistance R^2 , and then it divides, part passing through wire 225, contacts 75, relay 72, to ground or return at 26, and the other part passing from wire 90, through contacts 95, and magnet 73, to ground or return. Consequently prong 86, of the escapement 76, is still held in front of the stop 78, although not necessary, since the magnet clutch, at this time is inactive. Relay 72 continues to hold the contacts 74, open thereby preventing another circuit from being established through relay 27, the magnet clutch, the commutator segment 66, the ring 85, and wire 92. Therefore everything remains in this condition until the depressed key is released and current is cut off from wire 25 by the distributor relays returning to their normal positions. When this happens, however, relay 72, and escapement 76, return to their normal positions and the only difference is that now stop 78, is obstructed by the prong 113 of the escapement, and the contact spring 111, bears on commutator segment 66. The resistance R^2 is relatively high, say 10 ohms, as compared with the resistance of relay 27, which is, say 1 1/2 ohms. I also employ an extra set of contacts A⁴, which are normally closed but are opened by the escapement 76, when the latter is operated. These contacts control a shunt or branch circuit which includes an extra pair of contacts B⁴, normally open but closed upon each other when the relay 27 is operated, and which are in series with the winding of said relay. The function of this shunt or branch circuit is to keep the relay locked up to its oper-

ated position when the escapement has been operated and until the circuit is opened by the commutator 112.

Now suppose another key is depressed. Thereupon the distributor relays corresponding to the particular key which is depressed, connects the generator circuits of the selected character of current as determined by the particular relays, to the line springs 103, 105 and 107, as before described. Said relays also complete their own locking circuits, and close the battery circuit to wires 24, 25, as before explained. Now, however, the current flows through wire 25, relay 27, contacts 63, wire 64, commutator section 66, instead of 65, as before, thence, instead of continuing through ring 67, wire 68, and so on, as before, this circuit continues from segment 66, to ring 85, wire 92, contacts 74, and thence through wire 226, where it divides, one part continuing through the relay 93, to ground or common return at 26, and the other continuing through wire 94, another coil of magnet 73, and to ground or common return at 26. The completion of this circuit energizes the relay 27, which thereupon performs its functions, as and in the manner above described, of completing the distributor relay locking circuit. The completion of the circuit last above traced also energizes relay 93 and magnet 73. The energization of relay 93, causes contact 69, to be opened and contact 95, to be closed, while the magnet 73, performs its function, the same as above described, of operating the escapement 76, to permit the stop arm 78, in this instance, to pass, and to complete the magnetic clutch circuit, by opening the contact 63. Thereupon the sleeve 84, and drum 61, make another half revolution, again sending the desired group or combination of impulses over the line wire. When the half revolution of sleeve 84, is completed the commutator 112, again opens the clutch circuit and also the circuit of relay 27, and the sleeve 84 is arrested, and the distributor relay locking circuit opened, in the same manner as before explained. Since the contact spring 111, is now resting on commutator segment 65, the circuit of relay 27, and magnetic clutch 79, cannot again be established until the key is released and the distributor relays cut off the current from wire 25, for the reason that, until this current is cut off, relay 93 will continue to hold contacts 69 open and hence the circuit of commutator segment 65, remains open. Thus it will be seen that in the operation of the apparatus the relays 72 and 93, operate alternately, the change from the one to the other being effected by the commutator 112.

In Fig. 2 I have indicated diagrammatically the different wiring connections of the relay spools of the distributor. The locking coil for said relays and hereinabove referred

to, is indicated by the short line on the left hand side of each relay spool, indicated in Fig. 2. By tracing the windings and circuits from any one of the binding posts or terminals 35, as indicated in Fig. 2 of the drawings, to the ground of common return at 26, it will readily be seen that a different group or combination of three relays is included with each terminal 35. Take terminal 36, for instance, and suppose the circuit of battery 18, be completed to said binding post or terminal. Thereupon current will flow through the wires 228, 229, 230, 231, 232, to common return or ground at 26, and the relays 1, 8 and 10, will be included in this circuit. Similarly, it will be seen that each of the terminals 35, is included in circuit with a set, group or combination of three distributor relays.

For convenience in illustrating the manner of connecting the battery circuit to the terminals or binding posts 35, I have shown a few of the terminals at top of Fig. 1.

Referring now, to Fig. 1, reference signs 37, 38, 39, 40 and 41, designate keys of the key board, only a few of the keys being shown, but these are sufficient to illustrate the principles of operation of the apparatus. It will be observed that the circuit from the battery 18 (Fig. 3), to all the keys except one, namely the key indicated by reference sign 39, includes a switch 42. Normally this switch is closed and hence a battery current is supplied to one or another of the binding posts or terminals 35, whenever a key is depressed.

In practice, as each complete printing telegraph machine includes a sending and also a receiving apparatus, I arrange the receiver at the sending end to print simultaneously with the receiver at the distant end, and I arrange the switch 42, to be opened automatically by the carriage of the receiver at the sending end when such carriage reaches the end of a line. When this occurs the battery power is cut off from all the keys of the key board except the key 39, as above stated, the circuit of which does not include the switch 42. Consequently, after the carriage reaches the end of a line and strikes the switch 42, and opens it, the operation of any key of the keyboard except the key 39, will have no effect. The key 39, is designed to control the battery circuit in such manner and through the desired path to effect the proper group or combination of impulses necessary to return the carriage to its starting point for another line of printing, and the return of the carriage releases the switch 42, and permits the same to again close, thereby putting all keys in condition to be again operated to control the transmission of groups or combination of impulses. By this arrangement it is impossible for the printed letters to pile up on

top of each other at the end of a line in case the operator should fail to notice that his carriage has reached the end of its travel. It is obvious that other means for accomplishing this result or for notifying the operator that his carriage is approaching the end of its line movement, may readily be adapted to the apparatus.

As above indicated, the keys 37 and 38 are ordinary letter keys of the keyboard, and illustrate the action and operation of the keyboard. The key 39 is the carriage return key, and keys 40 and 41 are the type or carriage shift keys. I arrange a special circuit for these shift keys in order that they may properly perform the function of printing only capital letters or figures, and also of controlling the shifting of the type or carriage. In accordance with my invention I propose to arrange these keys and the circuits controlled thereby, in such manner that said keys may be held down or depressed, and while so held down or depressed, to permit of other keys being depressed and to perform their work notwithstanding the shift keys are held down in this respect differing from all the other keys, as above explained, and which have no effect when depressed, if another key is depressed. I also so arrange the circuits controlled by the shift keys, that when said keys are released, after being depressed, they complete circuit connections for sending suitable and proper combinations of current impulses to release the shifting mechanism which had previously been operated.

The electrical connections controlled by keys 40 and 41, are as follows: Upon depressing key 40, circuit is completed from battery 18, through switch 42, wire 43, the contacts of key 40, wire 233, relay 46, to ground or common return at 26. The energization of relay 46, closes the contacts 55 and 54. The closing of contacts 55 completes a circuit from battery 18, through wire 44, wire 234, contacts 55, wire 235, relay 47, wire 236, one winding of relay 48, to ground or common return at 26. The closing of contacts 54, completes circuit from battery 18, through wire 44, wire 234, contacts 54, wire 237, contacts 53, which remain closed until relay 47, is sufficiently energized, thence through wire 238 to binding post or terminal 39, and on through the corresponding group or combination of distributor relays. The completion of this last traced circuit is only momentary since as soon as the relay 47 operates, it opens contacts 53, thereby breaking said circuit. But the momentary completion of said circuit, as explained, is sufficient since the action of the distributor relays is so rapid that their locking circuits, above described are thereby closed and operate to hold the operated distributor relays in operated position before

the contacts 53, are broken. Thus, as long as key 40, is held down, its circuit through the distributor is broken, and hence other keys may be operated in the usual manner 5 while the key 40 is held depressed. The action of key 41 is similar in all respects with that above described with reference to key 40, except that, in this case, the depression of key 41, completes battery circuit through 10 switch 42, wire 43, the contacts of key 41, wire 239, relay 45, to ground or common return at 26. Relay 45, closes contacts 56 and 57. The closing of contacts 56 completes circuit from battery 18 through wire 15 44, wire 234, contact 56, wire 240, contacts 58, wire 241, terminal 60, and on through the distributor relays. The closing of contacts 57, completes the battery circuit through wire 44, wire 234, contacts 57, wire 20 235, relay 48, to ground or return. The energization of relay 47, opens contacts 58, thereby breaking the distributor circuit through terminal 60, but before this circuit is broken the locking circuits of the corresponding distributor relays have been completed 25 as in the case of the operation of key 40, above explained.

It is above noted that when either of the keys 40 or 41 is depressed a circuit is completed through relay 48. This relay, when energized, closes contacts 50 and 51, and said relay is maintained energized, that is, its circuit remains closed as long as either of the shift keys 40 or 41 is held down. When the depressed shift key is released, however, I provide means whereby a group or combination of impulses are sent to effect the starting up of the sender. To explain this operation it must be remembered, as explained above, 30 that relay 27, see Fig. 4, and which I call the unlocking relay, is always in the position shown, except during the time of revolution of the automatic sender, and no matter whether the operator continues to hold 35 a key down or not relay 27 will always return to its normal position as soon as the automatic sender has completed its work and shifts the commutator brush 111 from one segment of the commutator 112, to the 40 other, since the circuit of said relay is controlled by said commutator. The relay 27, when energized opens a circuit between the contacts 61, and 30, and closes a circuit between contacts 30, and 31, and when the 45 relay is in its normal position the last named contacts are opened while contacts 30 and 61, are closed. Battery 18, Fig. 3, is directly connected through wire 23, and wire 29, to contact 30. When the relay 27 is in its normal position current will flow 50 from battery to contact 30, to contact 61, and wire 97, Fig. 4, to wire 98, Fig. 1, and if a shift key is being held down, that is, if relay 48 is energized, then the current 55 will continue through wire 98, contacts 51,

and through the other winding of said relay 48 to ground or common return at 26, thereby virtually locking the relay 48 in its operated position until relay 27, is again operated, and irrespective of whether the shift key is released or not. If the shift key is held depressed, then the relay 27 will operate every time any other key of the key board is operated. The operation of another key would ordinarily operate relay 27, to 60 break the circuit of relay 48 but relay 48 has two circuits as above explained, one controlled by the relay 27, and one controlled by each of the shift keys, and hence said relay is held in operated position as long as 65 the shift key is held depressed and is only released when the shift key is released, and even then, the relay 48 remains in operated position until the relay 27 is again operated. But this occurs very quickly. When relay 70 47 returns to normal, by the release of the shift key, current will flow from battery 18, through wire 44, wire 234, wire 248, contacts 50, wire 249, contacts 52, wire 250, terminal 62, and on through the distributor, 75 thereby sending the required group or combination of impulses to effect the starting of the sender. When the sender is started up the circuit of relay 27, which is controlled by the commutator 112, is again completed 80 thereby causing said relay to open the circuit of relay 48, by separating contacts 30 and 61. Relay 48, thereupon returns to normal. The operation above described with 85 reference to starting the sender is the same 90 whichever key 40 or 41 is released, the same group or combination of impulses corresponding to the circuit of terminal 62, being sent in either case.

From the foregoing description it will be 95 seen that I provide an exceedingly simple printing telegraph apparatus wherein the proper performance of the functions of the various parts is insured, wherein the operation is carried on as rapidly as the keys of a 100 keyboard similar to that employed in a typewriting machine, can be manipulated, and every precaution is taken against interference of currents and wherein the various groups or combinations of impulses are 105 made up of currents of various characters, and wherein absolute control is maintained 110 over all working parts and circuits.

It is believed the operation of the apparatus will be fully and clearly understood 115 from the foregoing description taken in connection with the accompanying drawings.

It is obvious that many changes in the details of construction and arrangement of parts, and many variations therein might 120 readily occur to persons skilled in the art and still fall within the spirit and scope of my invention. I do not desire therefore, to be limited or restricted to the exact details shown and described, but my invention cov. 125 130

ers and includes broadly the various combinations and arrangements recited in the claims.

Having now set forth the object and nature of my invention, and a construction illustrative of an operative embodiment of the same, and having explained and pointed out the purpose, function and mode of operation thereof, what I claim as new and useful and of my own invention, and desire to secure by Letters Patent is:—

1. In a printing telegraph apparatus, a line circuit, in combination with a series of keys, a series of relays having circuits, each key adapted to control the circuit of a definite group of relays, circuits for electric impulses of differing character controlled by said relays, means whereby only one relay of each group may be effectively operated at a time, and means for connecting said impulse circuits to the line circuit.
2. In a printing telegraph apparatus, a line circuit, a series of keys, a series of relays having circuits, each key adapted to control the circuit of a predetermined group of relays, means whereby when one key is operated the operation of the other keys is rendered ineffective, circuits for electrical impulses of differing characteristics controlled by said relays, and means controlled by the relays for connecting said impulse circuits to the line circuit.
3. In a printing apparatus, a line circuit, a series of keys, a series of relays having circuits, each key adapted to control the circuit of a predetermined group of relays, means whereby when one key is operated the operation of the other keys is rendered ineffective, circuits for electrical impulses of differing characteristics controlled by said relays, and means controlled by the relays for successively connecting said impulse circuits to the line circuit.
4. In a printing telegraph apparatus, a series of relays having circuits, means for controlling the circuits of said relays in groups or combinations, means whereby when one group of relay circuits are in operation the other groups are rendered inoperative, electrical circuits for currents of differing characteristics controlled by said relays, a line circuit and sending mechanism for connecting said pressure circuits to the line, said sending mechanism also controlled by said relays.
5. In a printing telegraph apparatus, a series of relays having circuits, electric pressure circuits controlled by said relays, a line circuit and sending apparatus, also controlled by said relays for connecting said pressure circuits to line.
6. In a printing telegraph apparatus, a line circuit, a series of relays arranged in groups, connections for currents of differing characteristics, and having circuits,

means controlled by said relays for connecting said circuits to line, means for controlling the circuits of said relays in predetermined combinations and means whereby when one combination is in operation the others are rendered inoperative.

7. In a printing telegraph apparatus, a series of relays arranged in groups, a line circuit, electric pressure circuits, means controlled by said relays for connecting said circuits to line, and means whereby when one relay of a group is operated the other members of the same group are inoperative.

8. In a printing telegraph apparatus, relays arranged in groups, electric pressure circuits controlled by said relays, means for controlling the circuits of said relays in combinations, and means whereby, when a relay of one group is operated the other relays in the same group are rendered inoperative.

9. In a printing telegraph apparatus, electric pressure circuits, a line circuit, sending apparatus including contacts arranged to connect said pressure circuits to the line circuit in predetermined groups, and relays for controlling said sending apparatus.

10. In a printing telegraph apparatus, electric pressure circuits, a line circuit, sending apparatus including contacts arranged to connect said pressure circuits to the line circuit in predetermined groups, relays for controlling said sending apparatus, and key mechanism for controlling the circuits of the relays.

11. In a printing telegraph apparatus, electric pressure circuits controlling current pressures of varying character, a line circuit, sending apparatus for connecting the pressure circuits to the line circuit, relays operating to control the sending apparatus to effect such line connections in definite sequence and means whereby when one relay is operated the operation of the others is rendered ineffectual.

12. In a printing telegraph apparatus, electric pressure circuits controlling current pressure of varying character, a line circuit, sending apparatus for connecting said pressure circuits to the line circuit, key-controlled relays for controlling said sending apparatus to effect said connections in predetermined groups and means whereby when one key is operated the operation of the other keys is rendered ineffectual.

13. In a printing telegraph apparatus, electric pressure circuits for controlling current pressures of varying character, a line circuit, sending apparatus for connecting said pressure circuits to the line circuit, key-controlled relay mechanism for controlling the sending mechanism and means whereby when one key is operated the operation of the other keys is rendered ineffectual.

14. In a printing telegraph apparatus, electric pressure circuits for controlling current pressures of varying strength, a line circuit, means for connecting said pressure and line circuits, relays for controlling the connecting means, and key mechanism for controlling the circuits of said relays in predetermined groups.
15. In a printing telegraph apparatus, electric pressure circuits for controlling current pressures of varying strength, a line circuit, means for connecting said pressure and line circuits, relays arranged in groups for controlling said connecting means, and a key mechanism for controlling the circuits of said relays in predetermined order.
16. In a printing telegraph apparatus, electric pressure circuits, a line circuit, a sending apparatus for connecting said pressure circuits to the line, electrically operated clutch mechanism for operating said sending apparatus, circuit connections therefor, and a commutator for controlling said circuit connections.
17. In a printing telegraph apparatus, electric pressure circuits, a line circuit, a sending apparatus for controlling the connections of said pressure circuits to the line circuit, a commutator, line completing contact devices, means for successively closing said contact devices upon each other, an electrically operated clutch for controlling said commutator, the circuit of said clutch being controlled by said commutator.
18. In a printing telegraph apparatus, electric pressure circuits, a line circuit, and means for controlling connections of said pressure and line circuits including a rotatable drum, contacts adapted to be successively closed by said drum, an electric clutch for controlling said drum, and a commutator for controlling the circuit connections of said clutch.
19. In a printing telegraph apparatus, electric pressure circuits, a line circuit, a sending apparatus for controlling the connections of said pressure and line circuits, a magnetic clutch mechanism for controlling the operation of said sending apparatus, a circuit therefor, and a commutator for opening and closing said circuit.
20. In a printing telegraph apparatus, electric pressure circuits for currents of differing characteristics, a line circuit, and a sending apparatus for controlling the connections of said pressure circuits to the line circuit and including an electrically operated clutch device, a circuit therefor, and means for automatically opening and closing said circuit.
21. In a printing telegraph apparatus, electric pressure circuits, a line circuit, apparatus for controlling the connections of said pressure and line circuits, and including a sending apparatus, automatic escape-
ment devices for controlling the operation of said sending apparatus and alternately acting coils for controlling the escapement devices.
22. In a printing telegraph apparatus, electric pressure circuits, a line circuit, and a sending apparatus for controlling the connections of said pressure and line circuits, stop mechanism for controlling the operation of said sending apparatus and alternately acting coils for controlling said stop mechanism.
23. In a printing telegraph apparatus, electric pressure circuits, a line circuit, and a sending apparatus, said sending apparatus being operable in continuous direction, means for periodically arresting said sending apparatus, said means including stop devices, and alternately acting relays and a commutator for controlling said stop devices.
24. In a printing telegraph apparatus, electric pressure circuits for currents of differing characteristics, a line circuit, and a sending apparatus operating to connect the pressure circuits to the line, means for operating said sending apparatus in continuous direction, stop devices therefor, and alternately acting electrical devices for controlling the stop devices to automatically arrest said sending apparatus periodically.
25. In a printing telegraph apparatus, electric pressure circuits, and a line circuit, in combination with a sending apparatus including contacts, a rotary drum for closing said contacts successively, an electrically operated clutch for intermittently operating said drum, a circuit therefor, and a commutator for opening and closing said circuit.
26. In a printing telegraph apparatus, pressure circuits, and a line circuit, in combination with a series of contacts for controlling the connections of the pressure circuits to the line circuit, a rotary drum for closing said contacts upon each other in succession, and alternately acting means for intermittently rotating said drum in continuous direction including a clutch, and means for automatically stopping and starting the clutch.
27. In a printing telegraph apparatus, pressure circuits, and a line circuit, in combination with contacts, means for successively closing said contacts, a stop device for controlling said contact closing means, and alternately acting coils and a commutator for controlling the stop device.
28. In a printing telegraph apparatus, pressure circuits, and a line circuit, in combination with a sending apparatus including a series of contacts, a drum for closing said contacts, a sleeve carrying said drum, means for rotating said sleeve in continuous direction, including an electrically op.

- erated clutch, a circuit therefor, and a commutator for opening and closing said circuit, whereby the rotative movement of the sleeve is caused intermittently.
- 5 29. In a printing telegraph apparatus, pressure circuits, and a line circuit, in combination with a sending apparatus, including a continuously rotating shaft, a sleeve mounted on said shaft, means for intermittently coupling said sleeve to said shaft a circuit for said coupling means, and a commutator carried by said shaft for controlling said circuit.
- 10 30. In a printing telegraph apparatus, a sending apparatus including a continuously rotating shaft, a sleeve mounted thereon, magnetic clutch devices for coupling said sleeve and shaft, a commutator for controlling the circuit of said magnetic devices.
- 15 20. pressure circuits and a line circuit arranged to be connected together and means carried by said sleeve for controlling the connections of said pressure and line circuits.
- 25 31. In a printing telegraph apparatus, pressure circuits, and a line circuit, in combination with a sending apparatus including a continuously rotating shaft, a sleeve mounted thereon, a magnetic clutch for coupling said shaft and sleeve, a commutator carried by said sleeve and arranged to control the circuit of said magnetic clutch, and means carried by said sleeve for controlling the connections of said line and pressure circuits.
- 30 35. 32. In a printing telegraph apparatus, pressure circuits, and a line circuit, in combination with a sending apparatus, for coupling up the pressure and line circuits, and including a contact device, a magnetic clutch for operating said contact device and a commutator for controlling the circuit of said magnetic clutch whereby said contact device is intermittently operated.
- 35 45. 33. In a printing telegraph apparatus, a sending mechanism, including a contact controlling device, a magnetic clutch for operating said device and a commutator and co-operating contact springs for automatically controlling the circuit of said clutch.
- 40 50. 34. In a printing telegraph apparatus, a sending mechanism including a contact making device, a magnetic clutch for operating said device, an escapement mechanism for periodically arresting said contact device, a magnet for controlling said escapement and means for closing the circuit of said magnet in advance of the closing of the circuit of said clutch.
- 45 60. 35. In a printing telegraph apparatus, a sending mechanism including a contact device, an escapement for intermittently arresting said device, operating mechanism for said contact device and means for operating said escapement in advance of the action of said operating means.
- 50 65. 36. In a printing telegraph apparatus, a sending mechanism, including a continuously rotating shaft, a sleeve mounted thereon and carrying a commutator, a drum also mounted on said sleeve contacts controlled by said drum, stop arms carried by said sleeve, a magnetic clutch for coupling said sleeve to the shaft, an escapement operating with said stop arms, the circuit of said clutch being controlled by said commutator and automatic devices for completing the circuit of said clutch.
- 70 75. 37. In a printing telegraph apparatus, a sending mechanism including a magnetic clutch, a circuit therefor, and an escapement mechanism and means operated by said escapement mechanism for controlling the circuit of said clutch.
- 80 85. 38. In a printing telegraph apparatus, a sending mechanism, means for operating the same including a clutch, an escapement device for intermittently arresting said sending mechanism, said operating means being controlled by said escapement.
- 90 95. 39. In a printing telegraph apparatus, a sending mechanism including a contact device, electrical devices for operating said contact device, means for periodically arresting said contact device, said means arranged to control the circuit of said electrical devices.
- 100 105. 40. In a printing telegraph apparatus, a sending mechanism including a continuously revolving shaft, a sleeve mounted thereon, a clutch for coupling said sleeve to said shaft, a commutator carried by said sleeve and arranged in the circuit of said clutch, an escapement mechanism for periodically arresting the rotative movement of said shaft, means for operating said escapement mechanism and means operated by the said escapement for short circuiting said clutch.
- 110 115. 41. In a printing telegraph apparatus, a sending mechanism including a rotatable drum, means for rotatively actuating said drum in continuous direction, a stop mechanism for arresting said drum at each half revolution thereof, and including a magnet, a circuit for said magnet, a commutator for controlling said circuit, and contacts controlled by said drum.
- 120 125. 42. In a printing telegraph apparatus, a line circuit, pressure circuits, contact devices for connecting said line and pressure circuits, a sending mechanism including a drum, means for rotating said drum in continuous direction, electrically operated means for automatically arresting said drum at the completion of half revolutions thereof of said contact devices controlled by said drum.
130. 43. In a printing telegraph apparatus, a sending mechanism including a rotatable drum, means for rotating said drum in con-

tinuous direction, electrically operated means for arresting said drum at the completion of each half revolution thereof and a series of contacts arranged to be successively closed during the rotative movements of said drum.

44. In a printing telegraph apparatus, a sending mechanism, actuating devices therefor, stop arms for intermittently arresting said sending mechanism, said stop arms being of triangular shape, and a forked escapement device coöperating with said stop arms, and against which the edges of the triangular parts of the stop arms coöperate, and means for controlling said escapement device.

45. In a printing telegraph apparatus, a source of electric pressure, independent circuits therefor, a resistance arranged in one of said circuits, key mechanism for controlling all of said circuits in predetermined groups, devices for completing said circuits to the line and alternately acting magnets for automatically controlling said devices.

46. In a printing telegraph apparatus, a pair of generators, line circuit connections to the positive side of one of the generators, similar connections to the negative side of the other of said generators, a line circuit, a key mechanism, a rotatable drum, and a rotatable commutator for controlling said drum, said key mechanism, drum and commutator constituting devices for controlling connections of said generator and line circuits.

47. In a printing telegraph apparatus, a source of electrical pressure, circuits therefor, relays for controlling said circuits, said relays being arranged in groups, each of said circuits being controlled by one of the relays in each of the various groups, a sending mechanism, starting circuits therefor, said relays also controlling said starting circuits and means for controlling said relays.

48. In a printing telegraph apparatus, a source of electric pressure, circuits therefor, a series of relays arranged in groups, each of said circuits being controlled by one of the relays in each group, a line circuit and automatic devices for completing said pressure circuits to the line circuit.

49. In a printing telegraph apparatus, a source of electric pressure, circuits therefor, relays for controlling said circuits, said relays arranged in groups, coöperating members of each group controlling the said pressure circuits, a key mechanism for controlling said relays in predetermined combinations, a line circuit, and means for completing the pressure circuits as selected by said relays to the line circuit.

50. In a printing telegraph apparatus, a source of electric pressure, circuits therefor, contact devices arranged in said circuits,

relays for controlling said devices, key mechanisms for controlling said relays, a line circuit and automatic devices for completing the pressure circuits to said line circuits.

51. In a printing telegraph apparatus, a source of electric pressure, circuits therefor, relays for controlling said circuits, said relays arranged in groups, each pressure circuit being controlled by one relay in each group, a sending mechanism, a starting circuit therefor, said relays also controlling said starting circuit, and means whereby when any relay of a group is energized all the other relays of the same group are rendered inoperative.

52. In a printing telegraph apparatus, a source of electric pressure circuits therefor, relays for controlling said circuits, said relays arranged in groups, one relay of each group controlling each pressure circuit, and means for simultaneously energizing said relays in combinations including one relay of each group.

53. In a printing telegraph apparatus, a source of electric pressure, circuits therefor, relays for controlling said circuits, said relays arranged in groups, each circuit being controlled by one of the relays of each of the several groups, and means whereby when one relay of a group is energized all the other relays of the same group are rendered inoperative, means for energizing the said relays in predetermined combinations, a line circuit, and means for completing the pressure circuits to said line circuit.

54. In a printing telegraph apparatus, a source of electric pressure, circuits therefor, relays for controlling said circuits, a sending mechanism, a starting circuit therefor, said relays also controlling said starting circuit, means for controlling said relays and means for locking said relays when energized in their operated position.

55. In a printing telegraph apparatus, a source of electric pressure, circuits therefor, relays for controlling said circuits, a sending mechanism, a starting circuit therefor, said relays also controlling said starting circuit, means for controlling said relays, and a locking circuit for each relay.

56. In a printing telegraph apparatus, a source of electric pressure, circuits therefor, relays for controlling said circuits, a sending mechanism, a starting circuit therefor, said relays also controlling said starting circuit, means for energizing said relays in predetermined groups or combinations, and a locking circuit for each relay, said locking circuit being made by the energization of such relay.

57. In a printing telegraph apparatus, a source of electric pressure, circuits therefor, including contacts, relays for making and breaking said contacts, a sending mecha-

- nism, a starting circuit therefor, said relays also controlling said starting circuit, means for controlling said relays and a locking circuit for said relays, and means for automatically controlling said locking circuits.
- 5 58. In a printing telegraph apparatus, a source of electric pressure, circuits therefor, relays for controlling said circuits, sending mechanism for completing the pressure circuits to the line, locking circuits for said relays, means for controlling the energization circuits of said relays, and means operated by said sending mechanism for controlling said locking circuits.
- 10 59. In a printing telegraph apparatus, a source of electric pressure, circuits therefor, relays for controlling said circuits, means for energizing said relays in predetermined combinations or groups, a locking circuit for each relay, and contacts arranged in each locking circuit and operated by the energization of its associated relay, a sending mechanism for completing the line connection of said pressure circuits, a relay controlled by said sending mechanism for controlling all of said locking circuits.
- 15 60. In a printing telegraph apparatus, a source of electric pressure, circuits therefor, relays for controlling said circuits, means for controlling the circuits of said relays, a sending mechanism for completing said pressure circuits to the line, electric devices for controlling said sending mechanism, said relays controlling the circuits of said electric devices.
- 20 61. In a printing telegraph apparatus, a source of electric pressure, circuits therefor, relays for controlling said circuits, means for controlling the circuits of said relays in predetermined combinations, a sending mechanism for completing the pressure circuits to the line, electric devices for controlling said sending mechanism and contacts arranged in the circuits of said electric devices, said contacts controlled by said relays.
- 25 62. In a printing telegraph apparatus, a source of electric pressure, circuits therefor, relays for controlling said circuits, a sending mechanism, a starting circuit for said sending mechanism and means controlled by said relays for controlling said starting circuit.
- 30 63. In a printing telegraph apparatus, a source of electric pressure, circuits therefor, relays for controlling said circuits, a sending mechanism for completing said circuits to the line, a key mechanism for controlling the circuits of said relays and a starting circuit for said sending mechanism arranged to be closed by said relays when energized.
- 35 64. In a printing telegraph apparatus, a source of electric pressure, circuits therefor, means for controlling said circuits, a sending mechanism including a commutator, a starting circuit for said sending mechanism and including said commutator and means for controlling said starting circuit.
- 40 65. In a printing telegraph apparatus, a series of keys, a circuit controlled by each of said keys, a distributor and a sending mechanism controlled by said key circuits, and an automatic switch arranged in said key circuits.
- 45 66. In a printing telegraph apparatus, a series of keys, a circuit controlled by each key, a corresponding series of terminals, a distributor mechanism arranged in groups of elements, each group being controlled by the circuit through a terminal, and a sending mechanism controlled by said distributor elements.
- 50 67. In a printing telegraph apparatus, a source of electric pressure, circuits therefor, relays for controlling said circuits, energizing circuits for said relays, and key mechanisms for controlling said energizing circuits, and an automatic switch device arranged in the key controlled circuits.
- 55 68. In a printing telegraph apparatus, a source of electric pressure, circuits therefor, relays for controlling said circuits, energizing circuits for said relays, keys for controlling said energizing circuits and means whereby when any one of said keys is operated all the other key controlled circuits are inoperative.
- 60 69. In a printing telegraph apparatus, a source of electric pressure, circuits therefor, relays for controlling said circuits said relays arranged in groups, energizing circuits for said relays, a key mechanism for controlling predetermined combinations of said relays in said groups, and means whereby when any key is operated the key controlled circuits of the other relays are rendered inoperative.
- 65 70. In a printing telegraph apparatus, a source of electric pressure, circuits therefor, relays for controlling said circuits, energizing circuits for said relays, a series of keys, each key controlling the energizing circuits of a predetermined group or combination of relays, and means whereby when one key is operated, the energizing circuits controlled by the other keys are rendered inoperative.
- 70 71. In a printing telegraph apparatus, a source of electric pressure, a line circuit, a key mechanism for controlling the connections of said pressure and line circuits, and a carriage operated switch arranged in the key controlled circuits.
- 75 72. In a printing telegraph apparatus a line circuit, a source of electrical pressure, circuits therefor means for completing the pressure circuits to the line in combination with means for rendering said circuit completing mechanism inoperative when the printing apparatus has completed a line of printing.

73. In a printing telegraph apparatus, in combination with impulse selecting and line circuit completing devices of key devices, circuits controlled thereby, relays arranged in said circuits, contacts controlled by said relays, said contacts controlling the impulse selecting devices.

74. In a printing telegraph apparatus, the combination with a line circuit, and means for selecting and sending impulses thereto, of a shift circuit, a key therefor, and means whereby when the key is depressed, the shift circuit is first closed and then opened while the key is held depressed.

75. In a printing telegraph apparatus, the combination with a line circuit, of a shift key, a circuit therefor, means controlled by said circuit for sending electrical impulses to the line and means whereby when the key

is depressed it first completes and then 20 breaks the shift circuit.

76. In a printing telegraph apparatus, the combination with a line circuit, of a shift key, a circuit therefor, means controlled by said circuit for sending electrical impulses 25 to the line, and means whereby said shift key circuit is completed both when said shift key depressed and when released, and is broken when said key is completely depressed.

In testimony whereof I have hereunto set my hand in the presence of the subscribing witnesses, on this 27th day of July A. D., 1907.

FRANK D. PEARNE.

Witnesses:

FRANK JOHNSON,
L. M. SHIELDS.
